COMBINED CHILD'S FOUNTAIN TOOTHBRUSH AND HOLDER

Benjamin N. Yamada, Menlo Park, Calif., assignor to
William A. Anderson, San Francisco, and Raymond
H. Heiskell, San Mateo, Calif.

Filed Sept. 21, 1970, Ser. No. 25,105

Term of patent 14 years

Int. Cl. D4—02

U.S. Cl. D4—26

FIG. 1 is a view in perspective of a combined child's fountain toothbrush and holder showing the features of my new design;

FIG. 2 is an exploded view in perspective of the same showing the toothbrush portion removed from the holder;

FIG. 3 is a front view in elevation of the same;

FIG. 4 is a right side view in elevation of the same which is the same as the left side view;

FIG. 5 is a rear view in elevation of the same;

FIG. 6 is a top plan view of the same; and

FIG. 7 is a bottom plan view of the same.

I claim:

The ornamental design for a combined child's fountain toothbrush and holder, substantially as shown and described.
